UNITED STATES PATENT OFFICE.

HENRY LLOYD BEACH, OF MONTROSE, PENNSYLVANIA.

SAWING-MACHINE.

SPECIFICATION forming part of Letters Patent No. 429,837, dated June 10, 1890.

Application filed January 2, 1890. Serial No. 335,575. (No model.)

To all whom it may concern:

Be it known that I, HENRY LLOYD BEACH, a citizen of the United States, residing at Montrose, in the county of Susquehanna and State of Pennsylvania, have invented certain new and useful Improvements in Sawing-Machines, of which the following is a full and clear description, reference being had to the accompanying drawings, forming part of this specification, in which—

Figure 1 represents a perspective view of a sawing-machine embodying my invention. Fig. 2 is a transverse sectional view of the same on the line X X of Fig. 1. Figs. 3 and 4 are details of one means of locking the carriage to the main frame.

My invention relates to certain new and useful improvements in sawing-machines, and especially to that class adapted for cross-cutting and slitting purposes; and my invention consists in the constructions and combinations of devices which I shall hereinafter fully describe and claim.

To enable others skilled in the art to make and use my invention, I will now describe its construction and indicate the manner in which I carry the same out.

Referring to the drawings, A represents a frame-work of any desired and appropriate construction, having fitted to the upper portions of its sides suitable track-irons B, which may be fixed to the frame or may be fitted thereon to have a vertical movement, for a purpose I will hereinafter make known.

Upon the top of the frame A is placed a bed or carriage C, whose surface is slotted to receive the upper portion of the saw D, which is mounted on an arbor E, journaled below the bed or carriage in suitable boxes or bearings a on the main frame, the said arbor carrying a pulley E', to which power is applied in any well-known manner to rotate the saw at a high rate of speed.

The bed or carriage C is provided at or near its sides with track-irons F, and between these track-irons and the track-irons on the main frame I interpose free rolling bearings, each consisting of a shaft G, having no fixed bearings, but having a free rolling movement, and each shaft being unconnected with the others, so that the movement of one shaft is not controlled or affected by the others. These

shafts may be grooved or have fixed to one end a flat roller H and to the other a grooved roller H', which lies between the adjacent faces of the track-irons B and F, respectively, so that the groove in the shaft or face of the roller will be engaged by said tracks, thereby dispensing with two rollers at each end of the shafts or with double grooved or faced rollers, and simply fixing and cheapening the construction of the machine. This manner of mounting the bed or carriage provides for an easy movement of the same, reducing to a minimum the friction between the track-irons and dispensing with the power which has heretofore been necessary to move the bed or carriage upon its ways or tracks.

While the track-irons B on the frame A may be constructed similar to those on the bed or carriage, nevertheless I prefer to make them substantially as shown in Fig. 1, where they are shown as each forming part of a single casting having its front portion provided with a curved slot b, through which and across the frame the rod c passes, having at one end a head c' and at the opposite end a nut or hand-wheel c'' for clamping the track-irons B, and from the track-irons of the frame extend projections d, which are arranged at the ends of the tracks and serve as stops to limit the movements of the shafts or rollers, while other stops on the carriage limit the reciprocating movements of the bed or carriage.

Journalized in the upper portion of the main frame and near the front and rear portions thereof are two shafts I I', whose opposite ends have secured rigidly to them one end of suitable links J, whose opposite ends are secured pivotally upon pins or studs e, projecting from the track-irons B, and to the shaft I is keyed or otherwise rigidly secured an arm K, which extends downwardly and has an opening in its lower end to receive and pivotally secure a threaded bearing, through which the lower end of a screw-rod L passes, said screw-rod having its upper end passing through a pivoted bearing in a casting M on the front of the main frame A and provided with a hand-wheel N, as shown. From the description of these parts it will be seen that when the hand-wheel is turned the screw-rod L works through its bearings, thereby raising the arm K and rocking the shaft I in its bearing.

ings. This movement raises the links J at the front portion of the machine and thereby forces the track-irons upward, (the hand-wheel having been first released,) causing the rear links J to likewise move upward, and the track-irons and the bed or carriage, and interposed roller-bearing to be adjusted vertically with such relation to the saw that I am enabled to regulate under all possible conditions the depth of cut of said saw.

5 The track-irons B may be fixed instead of movable, and the machine may be almost instantly converted from a crosscut-machine to one adapted for "slitting" purposes by 15 simply locking the bed or carriage to some part of the main frame A—say to the front portion of the track-iron B—by means of a pivoted hook, (see Fig. 4,) slotted link, and set-screw, or other well-known means engaging 20 a stud or projection X on the carriage. The bed or carriage may also be provided with any desired form of gage.

A machine constructed as previously described is compact, may be cheaply constructed, and combines the function of a cross-cutting and slitting machine, while the mounting of the bed or carriage enables the operator to move the said carriage toward the saw with but little effort, even when the carriage is heavily laden.

Having thus described my invention, what I claim as new, and desire to secure by Letters Patent, is—

1. The combination, in a sawing-machine, 35 of a main frame, a carriage or bed, means for detachably connecting the carriage or bed with the main frame, whereby said carriage or bed may be moved or rigidly held, and rollers or wheels between the carriage or bed 40 and main frame, said rollers having no fixed bearings.

2. The combination, in a sawing-machine, 45 of a main frame, a vertically-adjustable carriage or bed, means for temporarily locking the carriage to the frame, whereby the machine is adapted for cross-cutting and slitting purposes, and a free roller-bearing between the carriage or bed and frame, said bearing consisting of shafts with fixed end rollers and 50 each shaft being independent and unconnected with the remaining shafts.

3. The combination, in a sawing-machine, of a main frame having movable track-irons, a bed or carriage having fixed track-irons, shafts without fixed bearings having rollers 55 provided with grooves in which lie the track-irons of the main frame and carriage, a saw-arbor and saw, and means for communicating power thereto, substantially as described.

4. The combination, in a sawing-machine, 60 of a main frame having track-irons adjustably secured thereto, means for adjusting said irons, a bed or carriage having track-irons, shafts beneath the bed or carriage having no fixed bearings and provided with rollers 65 at the ends having grooves engaging the track-irons of both the carriage and main frame, stops for limiting the movement of the rollers and carriage, and means for locking the carriage to a part of the main frame, 70 whereby the machine is adapted for cross-cutting and slitting purposes, substantially as described.

5. In a sawing-machine, the combination of the main frame, the track-irons fitted thereto, 75 having curved slots in the forward end, a rod passing through the slots and having a hand-wheel, the shafts I and I', having links or arms pivotally secured to said track-irons, an operating-screw and connection with the 80 shaft I for raising the track-irons vertically, a bed or carriage having track-irons, shafts with no fixed bearings beneath the carriage having a roller on each end engaging the tracks of the frame and carriage, and means 85 for locking the carriage to the frame when necessary, substantially as described.

6. In a sawing-machine, the main frame having adjustable track-irons and a carriage having fixed track-irons immediately over 90 and in line with the track-irons of the main frame, in combination with a free rolling bearing between the carriage and main frame, consisting of unconnected shafts having no fixed bearings, said shafts carrying upon 95 their ends rollers having grooves common to both tracks, substantially as described.

HENRY LLOYD BEACH.
